PRINTER CONTROL RELAY

James A. Spencer, Teaneck, N. J., assignor to
 Radio Corporation of America, a corporation of
 Delaware

Application May 7, 1940, Serial No. 333,714

12 Claims. (Cl. 178—88)

This invention relates to teleprinters.

Radio telegraph signals are subject to deformation by spurious additions to, or reductions of, the marks and spaces. When the mark is increased or decreased in length in this way, the spaces are naturally oppositely affected. This phenomena is due to the effects of the upper atmosphere on radio transmission and the additions or reductions are likely to occur at any point in the signal pulse. When the signal is reduced in the middle portion of the pulse, it is called a "split" and these splits are often of sufficient time-length to produce a spurious space effect in the printer.

It is an object of my invention to eliminate alterations in the marks and spaces in signal communication by a simple relay combination of lower cost than the usual rotating distributor.

Another object is to provide an automatic arrangement for eliminating the effects of splits and a visual hand control device for compensating for the lengthening or shortening of the signal pulses.

Another object is to devise a printer or other recording relay that will be prevented from responding to spurious space lengths below a pre-determined value, whereby splits do not affect the printer.

Another object is to devise a relay that can be readily controlled to increase or decrease the proportion of mark time to space time any desired amount.

Another object is to provide a visual indicator of the existing relation between the marking and spacing times of the received signals, with the provision of a regulator that permits the adjustment of this relation.

Other objects will appear in the following description, reference being had to the drawing in which:

The single figure of the drawing is a circuit diagram of a receiving system containing my invention.

Referring to the drawing, it will be assumed that the radio signals have been received in the customary way and transmitted from the receiving station to the local office, either as direct current pulses or tone signals, which latter are generally converted at the receiving station into direct current pulses, as in Patent 2,142,218 granted to Richard E. Mathes and myself January 3, 1939. The invention is not limited to any particular receiving and local re-transmission system, so it will be assumed that D. C. pulses

of the signal appear in resistance 1 by an action that need not be specifically described.

Amplifier 2 has the grid 3 and cathode 4 connected respectively to the negative and positive terminals of resistor 1 when a signal voltage appears therein. During the time the signal pulses appear in resistor 1, the negative voltage applied to the grid thereby is sufficient to block the tube. During a space or time between the signal pulses, the grid and cathode have the same potential and electron current can flow through the tube. The cathode lead of tube 2 is connected to the negative ground terminal through resistances 5 and 6.

Two amplifier tubes 7 and 8 have their cathodes connected together at 9 and their grids connected to different elements in the circuit to make one conduct only on signal marks and the other conduct only on signal spaces. This is accomplished by connecting the grid of tube 7 to the positive end of resistance 5 and the grid of tube 8 to the plate 10 of tube 11. The cathode terminal 9 is connected to ground through the resistances 12 and 13. The grid of tube 11 is then connected to the positive terminal of resistance 6. A resistance 14 is connected between the positive end of resistance 12 and the plate terminal of tube 11.

In referring to the positive and negative terminals of the resistances, it is not meant that these always have that polarity. It is meant that the polarity is that given when a potential drop occurs in the resistances due to current flow. When there is no drop, of course, both ends of the resistance elements have the same potential.

Any type of multi-element tube may be used in the places shown on the drawing and the ones given are merely symbolic. The cathodes are shown as equipotential cathodes and the heaters are of the usual construction. These have been omitted, as heating elements are so well known that there is no need to complicate the drawing by showing them.

The principal embodiment of my invention consists of two polar relays 15, 16. One line coil 17 of relay 15 is connected between the positive terminal 18 of the plate supply and the plate of tube 8. Another line coil 19 is connected between the terminal 18 and the plate of tube 7. The polarity of these coils when energized is such that when tube 7 conducts, the armature switch 20 is moved against space contact 21 and when tube 8 conducts it is moved against mark contact 22.

A positive terminal 23 of an appropriate source is connected to the contacts 21, 22 through resistances 24, 25, respectively, and the switch tongue 20 is grounded through the negative terminal of the source. Mark contact 22 is connected through condenser 26 and assisting coil 27 to the junction point 28 and thence through opposing coil 29 to the space contact 21.

In relay 16, the line coils 30 and 31 and an adjustable resistance 32 are connected between the mark contact 22 and the junction point 28. Coil 33 is connected between the positive terminal 34 of a suitable source and the grounded negative terminal through resistance 35. Coil 36 is connected between the positive terminal 34 and the negative ground terminal through resistance 37, which is contiguous with resistance 35. The slider 38 is connected between ground and these two resistances so that it simultaneously decreases one while increasing the other, when manipulated by hand. Coils 33 and 36 are so connected that they are in opposition and relay 16 can therefore be biased to either polarity or made neutral merely by sliding contact 38 on the resistances 35, 37.

The armature or switch tongue 39 of relay 16 is connected to the positive terminal 40 of a supply source and the space contact is connected to the negative ground terminal through coil 42 of an indicating device 43. A compensating resistance 43' is included in this circuit. The mark contact is connected through printer 44 and coil 45 to the ground terminal.

The indicating device 43 is essentially a double acting D. C. ammeter and when the spaces and marks are of normal length, the pointer 46 will take an average position, say, in the center of the dial. If the marks are lengthened, which of course decreases the spaces, the average current through coil 42 will be less than that through coil 45 and the needle will swing to, say, the right. When the marks are shortened the needle will then swing to the left. The multi-path or other atmospheric effects that produce these errors are sufficiently uniform over a period of time to enable an operator to counteract them by hand adjustments. In my invention he can do this by moving the slider 38 to simultaneously and oppositely vary the magnetic strength of the coils 33, 36, which may shorten or lengthen, as the case may be, the space period in respect to the mark period and vice versa.

The operation is as follows:

Suppose a signal space condition exists in resistance 1. This means that the grid 3 and cathode 4 will have the same potential and tube 2 is unblocked. Current therefore flows through the tube and applies positive potentials to the inputs of tubes 7 and 11 by the drop in resistances 5 and 6. These tubes therefore are unblocked and conduct current.

The passage of current through coil 19 in relay 15 causes switch tongue 20 to swing toward space contact 21. This contact had previously been against contact 22, so that condenser 26 was charged. As soon as the contact opens between the switch tongue and mark contact 22, and before it engages space contact 21, condenser 26 discharges through coils 27, 31 and 30 and aids coil 19 in throwing the switch tongue against space contact 21 but holds tongue 39 against mark contact 43''. Current now flows from positive terminal 23 through resistance 25, condenser 26, coil 27, to junction point 28, where it is met by current flowing through coils 30 and 31 of

relay 16. The resultant current then flows through opposing coil 29 to contact 21 and to ground. Coils 19 and 27 predominate over coil 29 and the switch tongue is held against contact 21 so long as the signal space continues. The energization of coils 30 and 31 also holds relay tongue 39 against space contact 41, after opening the circuit at the mark contact 43''. The opening of this circuit causes the printer to respond to the signal space in the intended way.

When the signal marking pulse terminates the signal space, the negative potential in resistance 1 blocks tube 2 and removes the positive drop in resistances 5 and 6. At the instant that this happens, the electron current of tube 7 is producing a negative drop in resistances 12 and 13. This drop is now sufficient to substantially block tubes 7 and 11 or to reduce the current to such low values that the negative potential in resistance 14 is insufficient to block tube 8. Tube 8, therefore, immediately conducts current and completely blocks tubes 7 and 11 by the increased drop produced in resistances 12 and 13 by its electron current.

The current in coil 17 and the absence of current in coil 19 now reverses main relay 15 and throws the switch tongue towards the mark contact 22. As soon as the circuit is interrupted at contact 21, condenser 26 discharges in the opposite direction through coils 30, 31 and 27. This aids coil 17 in pulling the switch tongue against contact 22 but holds tongue 39 against space contact 41.

As soon as contact is made at 22, current flows from terminal 23 through resistance 24, coil 29, to junction point 28, where it divides and part flows through coil 27 and the condenser 26 and the remainder flows through coils 31 and 30 and thence to ground through switch tongue 20. It will be noted that the current flowing through coil 27 is in the same direction as the previous discharge current, so that tongue 20 is held against mark contact 22. The current in coils 30 and 31 is, however, reversed, so that the tongue 39 is thrown against the mark contact 43''. This causes the printer mechanism to respond to a marking signal.

The purpose of the opposing coil 29 in relay 15 is to start the relay tongue 20 in its opposite movement just as soon as the current in line coil 17 or 19, as the case may be, dies down to a predetermined value with the decay of the mark signal and thus start the relay tongue in its opposite movement before the current builds up in the line coil in the opposite direction.

The discharge current of condenser 26 hastens the movement of tongue 20 when it starts away from a contact, but the effect of this discharge current on relay 16 is to delay the opposite swing of the relay tongue 39, for a purpose that will now be described.

Let it be supposed that due to atmospheric effects a "split" occurs in the intermediate portion of a marking impulse. This is a spurious space of reduced length and relay tongue 20 will swing to the left into engagement with space contact 21. However, relay tongue 39 will not be swung to the left, as it ordinarily would be, because the discharge current from condenser 26 holds the tongue against mark contact 43'' for a sufficient time to permit the switch tongue 20 to swing back against the mark contact 22 when the split ends. This action of the discharge current of condenser 26 can be suitably controlled by adjusting the resistance 32 in circuit with

coils 30 and 31. The action of the discharge current of condenser 26 does not shorten the signals. The effect is merely to shift them a slight amount. What is gained at the beginning is lost at the end, so the signal length does not change. The splits, however, are of such reduced length that they are affected only at the beginning.

Let it be supposed that the effect of the upper atmosphere is such that the signal pulses are lengthened, with the resultant shortening of the signal spaces. As already stated, this is a fairly slow effect and the operator can note from the position of the indicator needle 46 that it occurs. He therefore can counteract it by swinging the potentiometer slide 38 to increase the action of one coil and decrease that of the other in the pair of coils 33, 36 of relay 16. By watching this needle, the operator therefore can maintain the marks and spaces of substantially normal length.

The constants of the various units may, of course, have various values, but by way of example the following values may be given for a satisfactory installation:

The dot cycles of the printer signals are 22 cycles per second. Coils 17, 19, 30 and 31 are 1.15 henrys each. Coils 27, 29, 33 and 36 are 0.277 henry each. Resistances 24 and 25 are 1,000 ohms each. Resistance 32 is 4,000 ohms. Potentiometer 35, 37 is 1,000 ohms. The condenser 26 is 1 microfarad.

It will thus be seen that my improvement automatically takes care of interruptions of the signal in the center of the marking impulse and permits one, by hand-operated means, to offset the effects when produced at the ends of the marking impulse.

Obviously, the magnetic circuit of the relays need not be of the form shown in the drawing. This form has been chosen to more readily portray the action to the eye, with minimum reading of the description of the operation. This may take any form desired.

The coils and condenser need not be associated with the specific type of switch shown in the drawing. It will be apparent that the contacts 21, 22; resistances 24, 25; the terminal 23 and the negative ground merely constitute one form of reversing switch for the coils and condenser. This reversing switch may take any desired form, such as a double pole double throw switch or any other of its equivalents.

It will be apparent that various modifications may be devised for producing the desired result and therefore the invention is not to be limited to the specific disclosure.

Having described my invention, what I claim is:

1. A polar telegraph relay system comprising a reversing switch, a coil for reversing said switch upon its energization and de-energization, a second coil for accelerating the said action of the switch, a condenser, the accelerating coil and condenser being connected in series to said switch for reversal of current therein upon operation of the switch, a switch and a coil for operating the last-mentioned switch connected in shunt to the series circuit containing the accelerating coil and the condenser, whereby the condenser, upon the breaking of its circuit, discharges through the last-mentioned coil for delaying the operation of the second-mentioned switch.

2. A polar telegraph relay system comprising a reversing switch, a coil for reversing said switch upon its energization and de-energization, a second coil for accelerating the said action of the switch, a third coil for opposing said action, a con-

denser, the last-mentioned two coils and condenser being connected in series to said switch for reversal upon operation of the reversing switch, a switch and a coil for operating the last-mentioned switch connected in shunt to that part of the series circuit containing the accelerating coil and the condenser, whereby the condenser, upon the breaking of its circuit, discharges through the accelerating coil and last-mentioned coil for operating the reversing switch, upon the decay of current in the first coil, and for delaying the operation of the second-mentioned switch.

3. A polar telegraph relay system comprising a switch tongue, a pair of contacts engageable by said tongue, a line coil for operating the relay in response to incoming signals, a source of supply having one terminal connected to said contacts and the other terminal connected to said switch tongue, an accelerating coil and a condenser connected in series between said contacts, and a printer relay coil connected in shunt to the series circuit containing the accelerating coil and the condenser.

4. A polar telegraph relay system comprising a switch tongue, a pair of contacts engageable by said tongue, a line coil for operating the relay in response to incoming signals, a source of supply having one terminal connected to said contacts and the other terminal connected to said switch tongue, an accelerating coil, an opposing coil, a condenser, said accelerating coil, said opposing coil and said condenser being connected in series between said contacts, and a printer relay coil connected in shunt to that part of the series circuit containing the accelerating coil and condenser.

5. A polar telegraph relay system comprising a switch tongue connected to a potential of one sign, a pair of contacts engageable by said tongue, a line coil for operating the relay in response to incoming signals, an accelerating coil, an opposing coil, a condenser, resistances connected between said contacts and a potential of another sign, said assisting coil, said opposing coil and said condenser being connected in series between said contacts, and a printer relay coil connected in shunt to that part of the series circuit containing the accelerating coil and condenser.

6. A telegraph printer system comprising a printer switch, a coil for operating said switch, a coil and an adjustable resistance for biasing said switch toward opening or closing condition, means for energizing and de-energizing said coil in response to signal marks and spaces, and means to indicate the relation between the marking and spacing time periods of the message as it is received, whereby said resistance may be adjusted to counteract changes in said time periods.

7. A telegraph printer system comprising a printer switch, a coil for operating said switch, two additional coils, one aiding and one opposing the operating coil and means to vary the current in one of said additional coils for biasing said switch toward opening or closing condition, means for energizing and de-energizing the operating coil in response to signal marks and spaces, and means to indicate the relation between the marking and spacing time periods of the message as it is received, whereby said current may be varied to counteract changes in said time periods.

8. A telegraph printer system comprising a printer switch, a coil for operating said switch, two additional coils, one aiding and one opposing the operating coil and means to oppositely vary the current in said additional coils for biasing said

switch toward opening or closing condition, means for energizing and de-energizing the operating coil in response to signal marks and spaces, and means to indicate the relation between the marking and spacing time periods of the message as it is received, whereby said current may be varied to counteract changes in said time periods.

9. In a printer system, a printer polar switch, a reversing switch having an accelerating coil, a condenser, said condenser and accelerating coil being connected in series and the series branch connected in shunt with the operating coil of the printer switch across the contacts of the reversing switch.

10. In a printer system, a printer switch having an operating coil, a reversing switch having an accelerating coil, a condenser, said condenser and accelerating coil being connected in series and the series branch connected in shunt with the operating coil of the printer switch across a source of potential through the contacts of the reversing switch.

11. In a printer system, a printer polar switch, a reversing switch having stationary contacts and a movable member adapted to engage said contacts, an accelerating coil for the reversing switch, a condenser, said condenser and accelerating coil being connected in series and the series branch connected in shunt with the operating coil of the printer switch across the contacts of the reversing switch.

12. In a printer system, a printer polar switch, a reversing switch having an operating coil, an accelerating coil and an opposing coil, a condenser, said condenser, accelerating coil and opposing coil being connected in series across the contacts of the reversing switch, the operating coil of the printer switch being connected in shunt with the circuit branch containing the condenser and accelerating coil.

20

JAMES A. SPENCER.
